The ornamental design for a retainer for a patient repositioning system, as shown and described.

DESCRIPTION

FIG. 1 is a perspective view of an environment and first embodiment of a retainer for a patient repositioning system according to the present invention.

FIG. 2 is an enlarged perspective view of the retainer shown in FIG. 1.

FIG. 3 is a front view of the retainer shown in FIG. 2.

FIG. 4 is a right side view thereof; the left side view being a mirror image thereof.

FIG. 5 is a top view thereof.

FIG. 6 is a bottom view thereof.

FIG. 7 is a rear view thereof.

FIG. 8 is another enlarged perspective view of the retainer shown in FIGS. 1-7 but shown in an alternate position (open).

FIG. 9 is a front view of the retainer shown in FIG. 8, in the alternate position.

FIG. 10 is a right side view thereof; the left side view being a mirror image thereof.

FIG. 11 is a top view thereof.

FIG. 12 is a bottom view thereof; and,

FIG. 13 is a rear view thereof.

The broken lines adjacent to shaded or sectional portions are an unclaimed boundary of the design and form no part of the claimed design.

The dash-dot lines are shown for environmental purpose only and form no part of the claimed design.
